C. BROADBENT

MASSAGE IMPLEMENT

Filed Aug. 23, 1924

UNITED STATES PATENT OFFICE.

CHARLES BROADBENT, OF ATLANTIC CITY, NEW JERSEY, ASSIGNOR OF ONE-HALF TO
HARRY LINCOLN PARKER, OF GERMANTOWN, PENNSYLVANIA.

MASSAGE IMPLEMENT.

Application filed August 23, 1924. Serial No. 733,786.

The invention relates to improvements in massage implements, and more particularly a small portable implement adapted to be readily held in the hand of the user or operator, or placed upon an article of furniture and moved about at will.

It is the object of my invention to provide such an implement which combines a rotary motion with suction and thereby stimulates the skin more efficiently and to a greater degree than similar devices now on the market.

It is also my intention to provide an implement of this character that will be durable and simple in construction and extremely easy to manipulate, and one that can readily be moved from place to place as desired.

In the accompanying drawings which illustrate the construction of my massage implement,

20 Figure 1 is a sectional view thereof, and Figure 2 is a detailed plan view of the end of the suction cup.

Fig. 3 is a detailed perspective view showing the cup and its connections.

25 Referring now more particularly to the drawings, 1 is a housing of sheet metal adapted to enclose an electrical motor 2. This housing is preferably constructed as shown by the drawing with an enlargement 1¹ at one end. At the top or one end of the motor 2 and within the enlarged part 1¹ of the casing is located a suction fan 3 adapted to be driven by the motor. Electric wires 4 are provided for connecting the motor to a source of current, and a switch can be conveniently located, cutting the motor on or off as required. I also provide an exhaust 5 at one side of the casing 1 adjacent the fan 3.

Attached to the top of the enlarged portion 40 1¹ of the casing 1 and adjacent the fan is a flexible tube 6, the inner end of which has direct communication with the interior of the casing so that the fan 3 will suck air therethrough when driven by the motor. Within 45 the tube 6 is located and spaced therefrom a rotary drive cable 7 enclosed in a flexible housing 8. This cable 7 extends back through the housing and has driving connection preferably with the suction fan 3, although the same may be directly connected to the motor.

At the outer end of the tube 6 and cable 7 is located a rotary cup 9 secured to the drive cable 7 so as to be rotated thereby by pin 12 when the implement is in operation. X is a rigid metal ring to which the housing 8 is clamped by a wire clamp or the like 11. I also provide openings 10 at the base of the cup 9, which openings form a communication between the cup and the interior of the tube. The above describes the connection of the cup with the tube, housing and drive cable as clearly shown in Fig. 3 of the drawing, wherein it will be seen that the rotation of the drive cable and its flexible housing will impart a rotary movement to the cup 9 through pin 12, carried by the cable 7, engaging apertures in the base of the cup, and the cup is firmly maintained in place at the outer end of a flexible tube 6 by clamping the tube and the cup together by means of clamp 11. In operation, it will be readily perceived that as the fan is operated it will cause a suction through the tube 6 and cup 9 and will also drive the cable 7 to rotate the cup 9.

From the above description, it will be apparent that I have provided a simple, efficient massage device and one that not only stimulates the skin by the rotation of the cup but also adds materially to the stimulation of the skin by causing a suction to be combined with the rotation.

Having thus described my invention, what I claim is:

1. A massage implement, comprising a casing, an electric motor within the casing, a suction fan within the casing adapted to be driven by the motor, a hollow tube secured to the casing adjacent the fan, a rotary drive cable located within the tube having its inner end connected to the motor, and a massage cup at the outer end of the tube and cable, said cup having openings communicating with the interior of the tube and being rigidly connected to the cable to rotate therewith.

2. A massage implement of the character described, comprising a casing having an enlargement at one end, an electric motor within the smaller portion of the casing, a suction fan within the enlarged portion of the

casing adapted to be driven by the motor, a hollow tube secured to the casing adjacent the fan, a rotary drive cable located within the tube and having its inner end connected with the motor, a flexible housing within the tube and surrounding the cable, and a message cup at the outer end of the tube, the

cup having openings in its base communicating with the interior of the tube, said cup being rigidly connected to the cable to rotate therewith. 10

In testimony whereof I affix my signature.

CHARLES BROADBENT.
